(57) **CLAIM**

The ornamental design for an artificial structure for attracting fish, as shown and described.

DESCRIPTION

FIG. 1 is an isometric view of the artificial structure for attracting fish;

FIG. 2 is a front elevational view thereof, the back elevational view being a mirror image thereof;

FIG. 3 is a right side elevational view thereof, the left side being a mirror image thereof; and,

FIG. 4 is a top plan view thereof.
